UNITED STATES PATENT OFFICE

LAWRENCE H. OFFUTT, OF RASPEBURG, MARYLAND, ASSIGNOR TO THE D. R. S. COMPANY INC., OF BALTIMORE, MARYLAND

CIGARETTE HOLDER

Application filed April 15, 1929. Serial No. 355,215.

This invention relates to a cigarette holder and fire extinguisher, the primary object of the invention being to provide a device of this character including a base which is in 5 the form of an ash tray, and a removable box-like container in which the cigarettes are held.

Another object of the invention is to provide a cigarette fire extinguisher removably 10 held in position by the box-like cigarette container and prevented from tilting or moving laterally while in use, by the clamping action of the box-like container.

A still further object of the invention is 15 to provide a base including upstanding flanges with which the box-like container cooperates in holding the box-like container to the base.

Another object of the invention is the provision of a combined cigarette holder and 20 cigarette fire extinguisher made up of a plurality of detachable sections so that the containers and cigarette fire extinguishers may be interchangeable and made in quantities to vary the advertising matter used with the 25 device.

With the foregoing and other objects in view which will appear as the description proceeds, the invention resides in the combination and arrangement of parts and in the 30 details of construction hereinafter described and claimed, it being understood that changes in the precise embodiment of the invention herein disclosed, may be made within the scope of what is claimed, without departing 35 from the spirit of the invention.

Referring to the drawing:

Figure 1 is an elevational view through a cigarette holder constructed in accordance with the invention, the tray forming the base 40 of the holder being shown in section.

Figure 2 is an end elevational view of the box-like holder, showing a cigarette fire extinguisher supported thereon.

Figure 3 is a vertical sectional view through 45 the box-like cigarette holder, on line 3—3 of Figure 2.

Figure 4 is a sectional view taken on line 4—4 of Figure 3.

Figure 5 is a transverse sectional view 50 taken on line 5—5 of Figure 3.

Figure 6 is a perspective view of the box-like cigarette holder support.

Figure 7 is a perspective view of one of the cigarette fire extinguishers.

Figure 8 is a modified form of cover for 55 the container designed to support a match box.

Referring to the drawing in detail, the base of the cigarette holder is indicated by the reference character 5 and in the present 60 showing is in the form of an ash tray which may be of any desired construction. Extending upwardly from the central portion of the ash tray, is a post 6 to which the stationary bottom of the cigarette holder or 65 container, is secured. This bottom includes a lower horizontal section 7 and vertical end sections 8, the sections 8 being provided with longitudinal inwardly disposed flanges 9, while the lower section 7 is provided with 70 upstanding longitudinal flanges 10 disposed along the side edges thereof.

The upper portions of the flanges 9 are separated from the sections 8 by slots so that 75 fingers 9' are provided at the upper ends of the flanges 9, which fingers 9' are curved laterally to engage within depressions or openings formed in the sides of the container, to be hereinafter more fully described.

The reference character 11 designates a 80 box-like container, the bottom thereof being open so that the container may be positioned over the end member 8, the lower side edges 85 of the container being embraced by the flanges 10 to securely hold the container in position. The end walls of the container 11 are cut away from points adjacent to the lower edge of the container to points substantially intermediate the ends of the container defining flanges 12 that embrace portions of the end members 8. A cover indicated at 13 is designed for closing the upper 90 end of the container, the cover being of the slip-over type so that the cover may be readily and easily removed or replaced.

The cigarette fire extinguishers are supported at the upper ends of the end members 8, and as shown each of the extinguishers includes a plate 14 having a downwardly 95 extended portion 15 spaced from the plate 14 100

to permit the cigarette fire extinguisher to be positioned over the upper edges of the end member.

The side edges of the plate 14 of each cigarette fire extinguisher, are extended upwardly in spaced relation with each other, defining a pair of parallel flanges 16 so constructed that they will readily flex towards or away from each other to the end 5 that a cigarette passed between the flanges will be gripped therebetween and the fire of the cigarette extinguished. In order that a cigarette may be readily positioned between the flanges, the flanges diverge at their 10 upper ends.

It will also be seen that due to the construction of the container, the cut out portions provide clearances for the cigarette fire extinguishers to permit the container to 15 be positioned as shown by Figure 3 of the drawing.

As shown by Figure 8 of the drawing, a cover for the container is indicated by the reference character 10' and is provided with 20 a cut out portion of a size to permit a match box, such as shown at 11', to be positioned therein, it being obvious that it may be desirable to support a match box by the device instead of cigarettes.

Secured to the cover 10' are downwardly 25 extended fingers 12' formed with upwardly extended portions 13' which are adapted to contact with the inner section of the match box to elevate the upper end of the inner section above the upper end of the outer section 30 of the match box, as shown by Figure 8.

I claim:

1. A cigarette holder including a base, a bottom member supported by the base, said 40 bottom member including upstanding end members, cigarette fire extinguishers positioned over the upper edges of the end members, a container box-like in formation and having its end walls cut away throughout 45 portions of their lengths providing clearances, said cigarette fire extinguishing members being gripped by the container, and a cover for the container.

2. A cigarette holder including a base, a 50 bottom member supported by the base, end members extending upwardly from the bottom member, a box-like container having open ends, fitted over the end members of the bottom member, cigarette fire extinguishers 55 positioned over the upper edges of the end members, portions of the container engaging the fire extinguishers to hold them in position, and a cover for the container.

3. A cigarette holder including a base, a 60 bottom member supported above the base, said bottom member including upwardly extended end members, cigarette fire extinguishing members positioned over the upper edges of the end members, a bottom- 65 less container positioned over the bottom

member and having the end walls of the container cut away defining flanges, said flanges adapted to embrace portions of the cigarette fire extinguishing members to secure the cigarette fire extinguishing members in position, and a cover for the container.

In testimony that I claim the foregoing as my own, I have hereto affixed my signature.

LAWRENCE H. OFFUTT.
